MACHINE FOR OPERATING UPON WEBS OF MATERIAL.

1,316,064.

Specification of Letters Patent. Patented Sept. 16, 1919.

Application filed December 28, 1915. Serial No. 69,097.

To all whom it may concern:

Be it known that we, CHARLES R. SEYMOUR and OTTO M. HOCH, citizens of the United States, and residents of Rochester, in the county of Monroe and State of New York, have invented certain new and useful Improvements in Machines for Operating upon Webs of Material, of which the following is a specification.

10 This invention relates to machines for receiving a web of material and performing certain operations thereupon, such as cutting the same into predetermined lengths and trimming and creasing the web of material 15 or the blanks cut therefrom.

The object of the invention is to provide a machine of this type which is especially designed for receiving a web of single-faced or double-faced corrugated board, and to cut 20 the faced corrugated board into blanks or portions of predetermined length, and then to trim the edge portions of the blanks so formed, and if desirable, provide the blanks with the proper number of bending creases. 25 These operations are performed in proper sequence by mechanism, the parts of which are designed in a novel manner and are so related that they are automatically operated in timed relation. For this purpose, various auxiliary devices are associated with the 30 main machine, which auxiliary devices will be hereinafter described in detail in conjunction with the description of the main parts of the machine.

35 The improved machine disclosed herein was designed especially for receiving single-faced or double-faced corrugated board manufactured upon a machine constructed for the purpose, but not herein illustrated.

40 The present machine is designed to be located at the rear of the above-mentioned machine for manufacturing the lined or faced corrugated board, and when used in conjunction therewith, constitutes in effect, a 45 single machine. The rear portion of such machine, or, in other words, the mechanism which constitutes the subject-matter of the present application may be used for operating upon other materials than faced corrugated board, and, therefore, it may be used by itself or in combination with machines other than the type above mentioned. The forward portion of the machine forms the

subject-matter of a separate application and has associated therewith the necessary 55 mechanism for manufacturing the faced corrugated board and delivering the same to the feed end of the portion of the machine forming the subject-matter of this application. The portion of the machine herein 60 disclosed has associated therewith the mechanism for cutting the faced corrugated board into predetermined lengths and the mechanism necessary for trimming the cut lengths and providing them with bending creases. 65 Although the rear portion of the machine herein disclosed is not limited to the treatment of faced corrugated board, the following description will refer throughout to faced corrugated board as the treated material, for 70 the sake of convenience.

The invention is illustrated in the accompanying drawings, in which:

Figure 1 is a longitudinal vertical section through the central portion of the machine; 75

Fig. 2 is a broken plan view, partly in section, of the structure shown in Fig. 1;

Fig. 3 is an enlarged vertical and longitudinal section of the shear mechanism and the rear portion of the feed rolls; 80

Fig. 4 is an enlarged vertical and longitudinal section through the slitting or trimming and creasing mechanism;

Fig. 5 is a front elevation, partly in section, of the slitting and creasing mechanism 85 shown in Fig. 4;

Fig. 6 is a side elevation of the so-called take-away belts or discharge belts and the mechanism associated therewith;

Fig. 7 is a broken plan view of the structure shown in Fig. 6;

Fig. 8 is a plan view, partly in section, of the sheet trip mechanism employed for setting the shear mechanism in operation;

Fig. 9 is a side elevation of the structure 95 shown in Fig. 8, certain parts being broken away to expose underlying mechanism; and

Fig. 10 is a front elevation of the electric solenoid and its associated parts for tripping the shear operating mechanism, the 100 solenoid being controlled by the sheet trip shown in Figs. 8 and 9.

Referring particularly to Figs. 1 and 2, it will be seen that the various parts of the machine for operating upon the web of material are mounted upon a framework, de-

noted generally by the reference character A. Obviously, this framework may be constructed in any suitable manner to properly support the operating parts positioned 5 thereon.

At the forward end of the framework A are a plurality of pairs of feed rolls. In the present instance there are four pairs of such rolls, the rolls of the first pair being 10 shown at 1, those of the second pair at 2, those of the third pair at 3, and those of the fourth pair being shown at 4. As above stated, the faced corrugated board discharged from the forward portion of the 15 machine not herein shown is gripped by these rolls and fed to the present machine. The four pairs of rolls just mentioned may, therefore, be more properly termed "pull" rolls, as they pull the material from the rear 20 end of the machine for manufacturing the faced corrugated board and feed the same to the present machine.

The top rolls of the first three pairs are made adjustable toward and away from the 25 lower rolls of such pairs by mounting the journals of the same in bearing boxes 5 (Fig. 3) capable of vertical sliding movements in the side frames of this part of the machine. The lower roll of each pair is 30 mounted in stationary bearing boxes 6 over which the bearing boxes 5 are yieldingly supported by means of coil springs 7. It will be understood that there is an upper sliding box 5 at each side of the machine 35 for each upper roll of the first three pairs and a lower box 6 at each side of the machine for each of the lower rolls of the first three pairs, and that a spring 7 serves to support each upper box 5 upon the lower box 6. All of the upper boxes 5 are provided 40 with bosses 8, each of which is internally threaded to receive a rotatable screw shaft 9. Each of the screw shafts 9 is rotatably mounted in and extends upwardly 45 through a bearing bracket 10 mounted upon the corresponding side frame, and above such bracket each screw shaft is provided with a beveled gear 11. The beveled gears 11 of each pair are rotated from a transverse shaft 12 carrying two beveled pinions 13 to mesh with the two beveled gears 11 of each pair. There are, therefore, three transverse shafts 12, each of which carries two beveled pinions 13 for rotating the beveled gear 11 at each end of one of the rolls. Each of the transverse shafts 12 is provided 50 with a hand wheel 14, by means of which such shaft may be rotated to adjust the position of the corresponding upper roll toward and away from the underlying bottom roll. It will be obvious that the turning of any one of the shafts 12 will simultaneously rotate the screw shafts 9 at the opposite ends of the corresponding upper 55 feed roll to raise or lower the two boxes 5

in which such roll is mounted. The springs 7 serve to hold the upper rolls the proper distance away from the lower rolls and when the upper rolls are adjusted toward the lower rolls, they are moved against the tension of the springs 7. The adjusting mechanism just described is utilized to space the upper roll of each pair the proper distance from the corresponding lower roll to feed the faced corrugated board without crushing 75 the same.

It will be noted that the top roll 4 of the fourth pair of rolls is not adjustable by the same type of mechanism as that just described. The top roll 4 is mounted in upper sliding boxes 5 the same as the other top rolls, and the lower roll 4 is mounted in boxes 6 similar to the boxes 6 employed for the other lower rolls, and the upper boxes 5 are supported on the lower boxes 6 85 by means of springs 7, just as in the case of the first three pairs of rolls. Each of the top boxes 5, however, of the top roll 4 receives the threaded extremity of an arm 15, which extremity is locked to the box 90 5 by means of a lock nut 16. On each of the side frames is mounted a bracket 17 to which the extremity of a link 18 is pivoted. Each of the arms 15 is pivoted to the midportion of the corresponding link 18, as 95 shown at 19. The two links 18 are swung upon the brackets 17 to raise and lower the upper roll 4 by means of a lever 20 disposed at one side of the machine and rigidly secured to a rock shaft 21. The rock shaft 100 21 at each side of the machine carries a rock arm 22 connected by means of a short link 23 to the extremity of the corresponding link 18. The lever 20 has connected thereto, a chain or cord 24 (Fig. 1) which 105 may extend to an operator's station at the front portion of the machine. In the normal position of the parts, the toggles constituted by the arms 22 and links 23 are straight, in which position the arms 22 abut 110 against set screws 25. In this position of the parts, the top roll 4 is in its raised position and is spaced from the corresponding lower roll 4. The set screw 25, therefore, determines the spacing between these 115 rolls. In the normal position of the rolls 4 of the fourth pair, they pinch the faced corrugated board slightly and assist the first three pairs of rolls in feeding the same forward. As above stated, the extent of 120 this pinching action may be regulated in the case of the first three pairs of rolls by turning the hand wheels 14. When these wheels are turned in one direction, the upper boxes 5 of the top rolls of the first three 125 pairs will be lifted by the springs 7, and when turned in the opposite direction, the screw shafts 9 will force the top boxes 5 downwardly against the tension of the springs 7. The space between the rolls of 130

the fourth pair is adjusted to conform with the space between the rolls of the other pairs by turning the set screw 25. If, for any reason, there may be a break in the paper passing through the machine and it is desired to start a new portion of the web through the machine, the lever 20 is actuated to depress the top roll 4 and bring it into contact with the corresponding lower roll 4. It may also be desirable to do this in the event that the faced corrugated board passing between the feed or pull rolls is of less than normal thickness, as may be the case if the material for forming the corrugated filler gives out, in which event, the web would not be properly fed forward by the pull rolls. By actuating the lever 20, the top roll 4 may be quickly brought into closer relation with the corresponding bottom roll to compensate for the reduction in thickness of the web, and, therefore, the web will be fed forward and will not clog the machine. When the pull upon the lever 20 is released, the upper roll 4 will return to its normal position, due to the provision of the springs 7 which support the upper boxes of the top roll 4.

After the faced corrugated board leaves the pull or feed rolls, it is caused to pass between a pair of shear blades, the purpose of which is to cut the web transversely into predetermined lengths. To the rear of the shear mechanism is located the mechanism for trimming the web and providing the same with the necessary creases and to the rear of this creasing and trimming mechanism is positioned a trip device adapted to be engaged by the forward edge of the web to trip the shear mechanism and thus permit actuation of the same to perform a cutting operation upon the web. The shear mechanism thus constitutes that portion of the machine through which the web next passes after leaving the feed or pull rolls. The shear mechanism will, therefore, now be described.

Referring particularly to Figs. 1 and 3, it will be seen that the shear mechanism comprises a vertically reciprocating knife bar 26 extending transversely of the machine and supported at its extremities in vertically movable slides, one of which is shown at 27 in Fig. 3. The movable slides 27 are, in turn, mounted to reciprocate in side housings, one of which is shown at 28. Each extremity of the vertically reciprocating knife bar 26 is connected at 29 to a link 30, which, in turn, is pivoted at 31 to the extremity of the actuating lever 32. It will be understood that there is one of these actuating levers 32 at each side of the machine, as shown in Fig. 2. Each of the levers 32 is pivoted at 33 to a portion of the shear frame. As shown in Fig. 2, there is a shear frame 34 at each side of

the machine, and these frames are connected by means of a transverse girder 35. Each frame 34 has associated therewith the housing 28, above described, in which the movable knife bar reciprocates.

The lower knife bar is shown at 36 and is mounted at its extremities in the shear frames 34. The upper knife bar 26 carries the upper knife blade 37, and the lower knife bar 36 carries the lower knife blade 38, the two blades being properly positioned to cut the web transversely when the upper knife bar descends.

The two shear frames 34 and the connecting girder 35 are mounted to reciprocate as a unit longitudinally of the machine on guides 39 formed on the bed of the machine. The mechanism for vertically reciprocating the upper knife bar is also utilized to reciprocate the shear frames in order to cause the upper and lower knife bars to travel with the web of material while the latter is being cut. This is accomplished by connecting the ends of the actuating levers 32 remote from the knife bars to a crank shaft, the rotation of which causes oscillation of the levers 32 about their pivotal connections 33 as well as bodily longitudinal movement thereof. The crank shaft for accomplishing this is shown at 40. At each end, the crank shaft 40 is provided with a crank arm 41 pivoted to the extremity of the adjacent lever 32, as shown at 42. It is obvious that rotation of the crank shaft 40 will oscillate the levers 32 about their pivotal connections 33, and hence reciprocate the upper knife bar in a vertical direction. As the levers 32 are pivoted at 33 to the shear frames, the rotation of the crank shaft will also impart a horizontal reciprocating motion to the shear frames. It will be noted from Fig. 3 that when the crank pins 42 rotate from the position shown in Fig. 3 in an anti-clockwise direction, the shear frames, together with the upper and lower knife bars, will move in the same direction that the web of material is moving, and about the time the shear frames attain their maximum speed and are moving at about the same speed as the web of material, the cutting action will take place. This is due to the fact that the cutting action takes place when the crank pins 42 are at approximately their highest points, and at this time also the shear frames are moving at their maximum speed. The second half of each revolution of the crank pins 42 will, of course, return the shear frames to their normal position and return the upper knife bar to its raised position.

The operation of the shear mechanism is controlled from a trip device located at the rear portion of the machine, and denoted generally by the reference character 43 in Fig. 1. This trip device controls an elec-

tric solenoid circuit in which a solenoid, when actuated, permits engagement of the members of a clutch, which latter controls the rotation of the crank shaft 40.

5 The clutch just referred to for controlling the rotation of the crank shaft 40 is shown in Fig. 2, the member 44 of which is loosely mounted upon a clutch shaft 45, and the member 46 of which is keyed thereto. The 10 member 44 of the clutch may assume the shape of a pulley, so that a belt passing thereover will serve to drive the same. As will hereinafter appear, the pulley or clutch member 44 may be utilized as the main driving pulley of the machine. As shown in Fig. 2, the driven part 46 of the clutch is 15 yieldingly urged toward the driving part 44 of the clutch by means of a coil spring 47 interposed between a shoulder on the 20 clutch member 46 and a collar 48 secured to the clutch shaft. The opposite end of the clutch shaft 45 carries a pinion 49 meshing with a gear 50 mounted upon the crank shaft 40. When the clutch members 46 and 25 44 are in engagement, it is, therefore, obvious that the crank shaft will rotate to actuate the shear mechanism. Means is provided for normally holding the clutch members 46 and 44 out of engagement with 30 each other, but when such means is tripped or released, the crank shaft is allowed to make one revolution. This means comprises the mechanism now to be described.

35 Mounted upon the crank shaft 40 is a cam 51 (Fig. 10), the cam surface of which is formed upon one of the lateral sides of the cam. Upon this cam surface rides a cam roller 52 carried by a bracket 53, which is mounted to swing about the axis of a stub shaft 54. Mounted to swing about the axis of the same stub shaft 54 is a second bracket 55, to the extremity of which is pivoted a pawl 40 56 which normally engages a shoulder 57 formed on the bracket 53. It will be understood that the two brackets 53 and 55 swing about the axis of the stub shaft 54 independently of each other, but are normally held in the relative positions shown in Fig. 45 10 by the pawl 56. Mounted to oscillate 50 unitarily with the bracket 55 is a rock arm 58 which is connected by means of a link 59 to a yoke 60, which, as will be noted from Fig. 2, acts directly upon the clutch member 46 to slide the same upon the clutch 55 shaft 45. The arrangement of the parts is such that the clutch spring 47 tends to engage the clutch members 44 and 46, but the pawl 56 just described holds the clutch member 46 in its inoperative position through 60 the intermediary of the bracket 55, the rock arm 58, the link 59 and the clutch yoke 60. It is obvious, however, that if the pawl 56 were tripped, that is, if it were moved from engagement with the shoulder 57, the 65 bracket 55 would be allowed to move inwardly

toward the cam 51, and hence the clutch spring 47 would be permitted to engage the clutch members. Means is, therefore, provided for tripping the clutch in this manner. It is accomplished by means of an 70 electric solenoid, shown at 61, in Fig. 10. When energized, this solenoid attracts the core or armature 62 and serves to swing a link 63 upwardly about its pivotal connection 64. Connecting the mid-portion of the 75 link 63 with the pawl 56 is a link 65. When the solenoid is energized, the link 65 raises until the extremity of a slot 66 formed therein engages a pin 67 carried by the pawl 56. The pawl is, therefore, lifted and 80 the bracket 55 is permitted to swing inwardly toward the cam 51, thus permitting the clutch member 46 to engage with the clutch member 44, as above described.

The link 63 has pivoted thereto, a swivel 85 block 68, through which passes a rod 69 pivotally supported at its upper end, as shown at 70, to a stationary part of the machine. Two coil springs 71 are associated with the rod 69 in such a manner as to yieldingly 90 check the movements of the links 63 and avoid shock. These springs 71, therefore, act as buffer springs.

After the pawl 56 is tripped and the crank shaft 40 is set in motion by the engagement 95 of the clutch members 44 and 46, the cam 51 secured to the cam shaft, of course, rotates and brings a low portion of the cam adjacent the cam roller 52. The bracket 53 is then permitted to move inwardly a sufficient 100 distance to allow the pawl 56 to again drop behind the shoulder 57, it being understood that when the pawl 56 is first tripped and the bracket 55 moves toward the cam 51, the pawl 56 rides over the top of the shoulder 105 57. When the high part of the cam 51 again engages with the roller 52, the bracket 53 is swung backwardly to its original position, and as the pawl 56 now engages behind the shoulder 57, the bracket 55 is also returned 110 to its original position. The restoration of the parts in this manner to their original position disengages the clutch members 44 and 46.

As above stated, the electric solenoid 61 is 115 controlled from the sheet trip 43, which, in turn, is actuated by the front edge of the web of material. The operation of the shear mechanism is, therefore, automatic. It may sometimes be desirable, however, to trip the 120 shear mechanism by hand, and this may be done by providing a bracket 72 which is free to oscillate about the same axis 64 as the link 63. The bracket 72 is swung about this axis by means of a rod 73 which may run to the 125 side of the machine or any other point where it may be conveniently actuated. The bracket 72 carries a projecting arm 74 capable of engaging the link 63 to move the same upwardly when the rod 73 is moved to the 130

left in Fig. 10. The link 63, may, therefore, be moved upwardly by actuating the rod 73 in the same manner that it is moved upwardly by the solenoid, and hence the clutch mechanism may be tripped by hand by actuating the rod 73.

It will be noted from Fig. 10 that before the clutch mechanism is tripped, the high portion of the cam 51 engages with the roller 52. After the clutch mechanism is tripped, the crank shaft rotates until the high portion of the cam 51 again engages the roller 52, at which time the clutch members are disengaged. The crank shaft 40, therefore, makes one complete revolution during which the shear frames are moved forwardly and returned to their original positions and during which the upper knife bar descends to cut the web, and then returns to its raised position.

In order to prevent unintentional operation of the trip mechanism when working about the machine, a link 75 (Fig. 10) is provided having a slot 76 in its end portion in which a pin 77 carried by the bracket 55 engages. The pin 77 normally occupies such a position in the slot 76 that the link 75 does not interfere with the movements of the bracket 55. If the link 75 is moved to the left, however, in Fig. 10, the right-hand extremity of the slot 76 will engage with the pin 77 and prevent movement of the bracket 55, even if the pawl 56 is tripped. The link 75 may be so moved to the left and locked in such position by means of a hand lever disposed at the side of the machine, or at any other point where it may be conveniently actuated. As shown in Figs. 9 and 10, the solenoid 61 is electrically connected to the sheet-actuated trip 43. As shown in the drawings, this sheet trip is disposed near the rear end of the machine and lies in the path of movement of the web. In some instances, it may be more desirable to use two sheet trips than one, and, therefore, two of such sheet trips have been illustrated in the drawings. Their relation with respect to each other is best shown in Fig. 7, from which it will be noted that they are arranged to be simultaneously engaged by the forward edge of the web of material. As shown in Figs. 8 and 9, each sheet trip 43 comprises a casing or framework 78, which is adjustable longitudinally of the machine upon a rod 79. By turning the thumb wheel 80, the casing 78 may be shifted until it is brought to the proper position as shown by the calibrations 81 on the rod 79 and the pointer 82 carried by the casing and co-operating with the calibrations. The position of the sheet trip from the shear mechanism, of course, determines the length of the blanks cut from the web.

Mounted to rock in the casing 78 is a transversely extending shaft 83 carrying at each end an upstanding arm 84. The upper

ends of the arms 84 are connected by a transversely extending sheet engaging plate 85 arranged to be engaged by the front edge of the web of material. When so engaged, the arms 84 are swung backwardly and the shaft 83 is, therefore, oscillated. The oscillation of the shaft 83 serves to shift a rock arm 86, to the upper end of which is pivoted a pawl 87. The pawl 87 normally engages behind a tooth 88 formed on the flange 89 of a sleeve 90, said sleeve being loosely mounted upon the shaft 83. When the pawl 87 moves forwardly with the arm 86, it, therefore, turns the sleeve 90 upon the shaft 83, but this movement is in opposition to the action of two coil springs 91 connected to the rear portion of the casing and to two depending arms 92 and 93, the arm 92 being carried by the sleeve 90, and the arm 93 being a depending portion of the arm 86 which is rigidly attached to the shaft 83. The sleeve 90 is rotated sufficiently far by the pawl 87 to bring two oppositely disposed contact shoes 94 into engagement with corresponding electric contacts 95. After this contact is made, an upwardly projecting arm 87' associated with the pawl 87 strikes an abutment 96 and serves to lift the pawl 87 out of engagement with the tooth 88. One of the coil springs 91 then returns the sleeve 90 to its original position and the electrical contacts between the parts 94 and 95 are broken. The arms 84 continue to swing downwardly to such an angle that the web passes over the same, and when the blank cut from the web has passed completely over said arms, they are returned by the other spring 91 to their original upright position in readiness to be engaged by the forward edge of the next blank.

The return movement of the sleeve 90 is yieldingly checked by means of a coil spring 97 coaxially disposed on a pin 98. A projection 99 associated with the sleeve 90 engages the pin 98 near the end of the return movement of the sleeve, and as the pin 98 is yieldingly held in the position shown in the drawings, the return movement of the sleeve 90 is yieldingly checked.

In the normal position of the parts, the contact shoes 94 are normally out of engagement with the contacts 95, as best shown in Fig. 9. These shoes are mounted to rotate unitarily with the sleeve 90, so that rotation of said sleeve brings each contact shoe 94 into engagement with the corresponding contact 95. The contacts 95 are carried by arms 100, to which the electric current is conducted from binding posts 101. The electric wires from the solenoid 61 are connected to these binding posts and the parts within the casing 78 are properly insulated to establish a proper path for the electric current from each binding post 101 to each contact 95.

When two sheet trips are employed, both of them may be connected in the same electric circuit, the latter being so arranged that the actuation of either trip will operate 5 the solenoid. The manner of electrically connecting the sheet trips with the solenoid is diagrammatically illustrated in Figs. 9 and 10.

After passing through the shear mechanism, 10 the web passes through the slitting and creasing mechanism, best shown in Figs. 1, 4 and 5. The slitting and creasing mechanism comprises two pairs of mandrels or shafts, upon which coöperating cutting disks 15 or knives and creasing blades are positioned. These shafts are arranged one above the other in a vertical row, and means is provided for shifting the position of all of the shafts as a unit to bring either pair of shafts 20 into such position that the web will pass through or between the cutting and creasing blades thereon. In this way, while one pair of shafts with the cutting and creasing blades thereon are operating upon the web 25 of material, the cutting and creasing blades on the other pair may be set for the next job.

The shafts above referred to, upon which the creasing and cutting blades are mounted, 30 are shown at 102, 103, 104 and 105. All of these shafts are mounted in vertically slideable side housings shown at 106 and 107. The housings 106 and 107 are mounted to slide in frames 108 and 109, respectively, 35 each of these frames being provided with guides 110, upon which the housings slide. Each of the housings 106 and 107 has associated therewith a rack 111, the teeth of which mesh with the teeth of a pinion 112 40 mounted upon each end of a transversely extending shaft 113. The shaft 113 is mounted in the frames 108 and 109 and may be rotated by means of a crank applied to its extremity 114 (Fig. 2). When this shaft is rotated, 45 it is obvious that the housings 106 and 107 will be raised and lowered in the side frames 108 and 109. In order to facilitate movement of the housings 106 and 107, the counter-weight 115 is provided at each side of 50 the machine mounted upon the end of a lever 116, which is pivoted at a mid point 117 to the frame of the machine. The free end of each lever 116 is connected by means of a link 118 to the base of the corresponding 55 housing. At one side of the machine, one of the links 118 is pivoted to the housing 107, and at the other side of the machine, a similar link is pivoted to the housing 106 (see particularly Fig. 1). The counter-weights 60 115 counter-balance a portion of the weight of the housings 106 and 107 and the parts carried thereby.

The shafts 102 and 103 constitute the upper pair of coöperating shafts and the 65 shafts 104 and 105 constitute the lower pair

of coöperating shafts. As best shown in Fig. 5, the upper pair of shafts carry the desired number of coöperating knife disks 119 to slit and trim the web and also the desired number of coöperating creasing blades 70 120 to form bending creases in the web. Likewise the lower pair of shafts 104 and 105 carry coöperating cutting or trimming knife disks 119' and a number of creasing blades 120'. The location of the knife disks 75 and the creasing blades upon the shafts or mandrels depends upon the character of the blank to be produced. When the housings 106 and 107 are in their lowermost position, the upper pair of shafts are in position to 80 have the web fed therebetween, and, therefore, the knives and creasing blades upon the upper pair of shafts will operate upon the web of material. The housings may be held in this position by means of a pin 121 85 mounted at each side of the machine in the frames 108 and 109. The extremity of the pins 121 engages in openings 122 of the housings to lock the same in position and before the housings can be moved, it is obvious 90 that the pins 121 must first be withdrawn against the tension of coil springs 123 which normally hold the pins in their operative position. While the upper pair of shafts 95 and the creasing and slitting blades thereon are being used to operate upon the web, the creasing and slitting blades upon the lower pair of shafts may be properly positioned for the next job. When the next job is started, the housings are raised by the mechanism above described to bring the lower pair of shafts into operative position, and then the creasing and slitting blades upon the upper pair of shafts may be re-positioned, if desired. When the housings are 100 in their raised position, the locking pins 121 are adapted to engage in openings 122' to support the housings in this position.

The lower shaft 103 of the upper pair and the upper shaft 104 of the lower pair are 110 mounted in bushings in the housings 106 and 107, but the upper shaft 102 of the upper pair and the lower shaft 105 of the lower pair are mounted in sliding bearing boxes 124 and 125, respectively. It will be understood that there is an upper sliding bearing box 124 at each side of the machine for the topmost shaft, and likewise a sliding bearing box 125 at each side of the machine for the lowermost shaft. These bearing 120 boxes are mounted to slide vertically in the housings 106 and 107 to adjust the distance between the two shafts of the upper pair, and the two shafts of the lower pair. Each of the two upper bearing boxes 124 has an 125 internally threaded hub portion 126 to receive the extremity of a threaded screw shaft 127. There are two of these screw shafts, one being arranged at each side of the machine for each upper bearing box 124. 130

Each of the screw shafts is rotated by means of a beveled gear 129 driven from a beveled pinion 130, the two beveled pinions 130 for driving the two beveled gears 129 being mounted upon a transversely extending shaft 131, best shown in Fig. 5. This shaft may be rotated in any suitable manner, such as by applying a crank to the extremity 132 of the shaft. By rotating the shaft 131, it is obvious that the upper bearing boxes 124 will be raised and lowered to adjust the position of the shaft 102 with respect to the shaft 103. A similar arrangement of parts, comprising beveled gears 129' meshing with beveled pinions 130' mounted upon a transversely extending shaft 131', serves to adjust the lower bearing boxes 125 in the same manner as above described in connection with the upper boxes to vary the distance between the shafts 104 and 105 of the lower pair. The shafts 131' may be actuated by applying a crank to the extremity 132' thereof.

The position or spacing of the cutting or slitting and creasing blades upon the shafts which carry them may be facilitated by the provision of a scale 133, shown in Fig. 4. This scale runs transversely of the machine and normally occupies the position shown in Fig. 4. It is supported near each end by a bracket 134 pivotally mounted upon a rod 135 which is fixedly carried in the adjacent housings, as shown. Each bracket 134 is normally locked to its pivotal support 135 by means of a set screw 136, and, therefore, the scale 133 is normally held in the position shown in Fig. 4. By loosening the set screws 136, however, the scale 133 may be raised or lowered to bring it adjacent to the blades of the lower shaft of the upper pair, or the upper shaft of the lower pair. After the cutting and creasing blades are set on either of these two shafts, the blades on the coöperating shaft may be set accordingly.

In order to guide the forward edge of the web between the cutting and slitting blades, a guide plate 137 is provided (Figs. 1 and 4), which serves to lift the forward edge of the web and direct it between the cutting and creasing blades.

The lateral edge portions trimmed from the web of material by the trimming knives may be deflected downwardly by a so-called trim deflector 138, mounted at each side of the machine. These deflectors direct the trimmed portion of the web downwardly toward the base of the machine. The trimmed portion of the web is then engaged by a plurality of discharge belts operated at such speed as to discharge the blank formed by the cutting of the web by the shear mechanism at a greater rate than the web is normally fed through the machine. Therefore, after each blank passes over the sheet trip 48, the trip arms associated therewith have

time to raise to their normal position before the forward edge of the blank approaches the sheet trip.

These discharge belts or so-called take-away belts and the parts of the machine associated therewith are best shown in Figs. 1, 6 and 7. Referring to these figures, it will be seen that the discharge belts are shown at 139 and pass over pulleys 140 and 141 arranged at the forward end and rear end, respectively, of the discharge table. Above the discharge belts 139 are arranged a plurality of weighted rollers 142, there being four of such rollers arranged in a horizontal series for each of the discharge belts 139, as best shown in Fig. 7. These rollers are mounted upon pivoted arms 143 carried by brackets 144 mounted upon the frame of the discharge table and serve to hold the web in contact with the discharge belts. The end rollers 142 of each series are positioned over the corresponding pulleys, over which the belts pass and the intermediate rollers 142 are positioned over rollers 145 located below the discharge belts and supported by brackets 146. The rollers 145 serve to support the belts 139, it being understood that said belts pass between the rollers 142 and 145 and that the web of material is supported by the belts and passes under the rollers 142. It is while the web is carried by these discharge belts that the forward edge of the web strikes the sheet trips. For this reason, the sheet trips are positioned between the discharge belts, as may be seen from Fig. 7, and the trip arms project upwardly beyond the plane of the discharge belts, as shown in Fig. 6.

Arranged in front of each of the sheet trips is a guide bracket 147, which serves to guide the forward edge of the web into contact with the trip arms of the sheet trip. Each of these brackets or castings 147 is carried by a rod 148 which runs longitudinally of the discharge table and which is pivoted at its forward end to the frame of the discharge table, as shown at 149. The rear end of each of the rods 148 is supported from a depending link 150.

The arrangement of the gears for driving the various parts above described has yet to be considered. Running longitudinally of the machine at one side thereof is a shaft 151 (Fig. 2) carrying a beveled pinion 152 meshing with a crown gear 153 secured to the face of the pulley 44. The rotation of the pulley 44 by a belt passing thereover, therefore, serves to drive the shaft 151 and the rotation of this shaft may be utilized to drive the other parts of the machine. As above stated, however, the machine disclosed herein is designed to be used at the rear of a machine for making faced corrugated board and the shaft 151 may, therefore, extend forwardly to such machine and 130

be driven therefrom. In this instance, the shaft 151 will constitute a driving shaft and will serve to drive the pulley 44 through the meshing gears 152 and 153. It is obvious 5 that under these circumstances, the pulley 44 need not be driven by means of a belt passing thereover.

The feed or pull rolls at the forward portion of the machine are driven from a shaft 10 154 which loosely carries a beveled gear 155 meshing with a beveled pinion 156 upon the shaft 151. A clutch 157 serves to connect or disconnect the gear 155 with the shaft 154. This clutch may be operated by means of a 15 pivoted lever 158 which, in turn, may be actuated by means of a rod 159 running to the side of the machine and actuatable by a handle 160 (Fig. 2). The shaft 154 carries at its end remote from the gear 155, a 20 pinion 161 which meshes with two gears 162. Each of these gears is mounted upon a shaft 163 which extends back to the drive side of the machine. At this side of the machine, each of the shafts 163 carries a 25 pinion 164, which serves to drive a gear 165 mounted upon one of the shafts of each pair of pull rolls. It will be understood that the two pull rolls of each pair are geared together by two gears 165 and that as one of 30 such gears of each pair is driven by an adjacent pinion 164, all of the feed rolls are positively driven.

Running parallel with the rear portion of the machine is a shaft 166 geared to the 35 shaft 151 by means of the meshing gears 167 and 168 (Fig. 2). The shaft 166 carries a beveled pinion 169 meshing with a beveled gear 170, which is utilized for driving the slitting and creasing shafts. The 40 gear 170 is loosely mounted upon a shaft 171 and may be operatively connected thereto by clutch mechanism actuated by means of a pivoted lever 172, which, in turn, is operated by means of a rod 173 running to 45 the side of the machine where it carries a handle 174. The shaft 171 at its end remote from the gear 170 carries a pinion 175 meshing with a gear 176. The gear 176, as shown in Figs. 2 and 5 rotates integrally 50 with a pinion 177, which is adapted to mesh with either the gear 178 mounted upon the extremity of the lower shaft of the upper pair of slitting and creasing shafts or with the gear 179 mounted upon the lower shaft 55 of the lower pair. When the four creasing and slitting shafts 102, 103, 104 and 105 are in their lowermost position, the gear 178 carried by the lower shaft of the upper pair meshes with the pinion 177, and, therefore, 60 the upper pair of shafts are positively driven. The two shafts of each pair are intergeared by means of the meshing gears 180 carried by the ends of the shafts remote from the gears 178 and 179. The upper pair 65 of gears 180 connect the two upper shafts

and the lower pair of gears 180 connect the two lower shafts. When the four slitting and creasing shafts are in their raised position, the driving pinion 177 meshes with the gear 179 carried by the lower shaft of the 70 lower pair, and, hence, the two lower shafts will be positively driven. By this arrangement of gearing, the two slitting and creasing shafts which happen to be in operative position will be the two shafts which are 75 positively driven, at which time the other two shafts will be disconnected from the driving means.

The rear extremity of the shaft 166 carries a pinion 181 meshing with a crown gear 182 loosely mounted upon a transverse shaft 183. The gear 182 may be operatively connected to the shaft 183 by means of clutch mechanism actuated by the pivoted lever 184. The shaft 183 carries the rear pulleys 85 141 over which the discharge belts pass, and, therefore, rotation of the shaft 183 actuates the discharge belts.

As described above, the crank shaft 40 from which the shear mechanism is operated 90 makes one revolution, and is then disconnected from its driving mechanism by the disengagement of the clutch members 44 and 46. In order to insure a prompt stoppage of the crank shaft 40, when the clutch members 95 44 and 46 are disengaged, the slidable clutch member 46 is caused to bear against friction brake mechanism to stop the rotation of the member 46 when it is disengaged from the clutch member 44. For this purpose, the 100 clutch member 46 is provided with a flange 184 adapted to bear against the friction surface 185 of two yieldingly-mounted slidable rods 186 and 187. These rods are yieldingly urged toward the clutch member 46 by 105 means of the coil springs 188 and 189, but the inward movement of these rods is limited by the nuts 190 and 191 carried by the two rods, respectively. The friction surfaces 185 are, therefore, spaced from the flange 184 110 when the clutch members are in engagement, but when the clutch member 46 is thrown out of engagement with the clutch member 44, the flange 184 will engage with the friction surfaces 185 and the rotation of the 115 shaft 45, and hence the crank shaft 40, will be immediately arrested.

The operation of the machine is as follows. The web of faced corrugated board or other material is fed to the machine by the 120 feed or pull rolls 1, 2, 3 and 4, and fed between the upper knife bar and the lower knife bar of the shear mechanism. The web then passes through one pair or the other of the slitting and creasing shafts. The forward edge of the web strikes the upstanding trip arms 84, or rather the plate 85 secured to said arms, and completes the electric circuit in the sheet trip 43 to energize the electric solenoid 81. The latter then trips the 125 130

actuating means for the shear mechanism which then moves forwardly with the web of material, during which movement the upper knife bar descends to cut the web transversely. The cutting action will take place when the shear mechanism attains the same speed as the speed of the web passing through the machine. The cut portion of the web or the blank formed by cutting the web, part of which lies to the rear of the trimming and creasing mechanism and part of which lies to the front thereof, is then drawn completely through the trimming and creasing mechanism and discharged by the belts at a greater speed than the speed at which the main body portion of the web moves. The arms 84 of the sheet trip or sheet trips are held down by the blank until the blank passes completely over the sheet trip. As the blanks are discharged from the machine faster than the main body portion of the web is fed, there will occur a space between the rear edge of each blank and the forward edge of the web. The arms of the trip mechanism, therefore, have a chance to rise after the blanks pass over the same to be in position for engagement by the forward edge of the oncoming web. When the forward edge of the web again engages the arms of the trip mechanism, the shear mechanism is again tripped to cut another blank from the web, and this operation is repeated as long as the parts are in motion.

During the passage of the web through the trimming and creasing mechanism, the end pairs of knives trim the edge portions of the web and the intermediate pairs of knives divide the web longitudinally into the desired number of strips. If desired, the intermediate sets of knives may, of course, be omitted and the web not divided longitudinally. The creasing blades mounted upon the slitting and creasing shafts provide the web with the desired number of creases, if it is desired to crease the blanks. If it should be desired to produce plain blanks without creases, the creasing blades may, of course, be omitted. The detail operation of each part of the machine will be obvious from the description, and, therefore, need not be repeated.

The preferred form of the machine has been specifically described, but it will be obvious that the parts of the machine may be constructed in other ways than that described, without departing from the spirit or scope of the invention as defined in the accompanying claims.

What we claim is:—

1. In a machine of the kind described for operating upon a web of material, the combination of means for slitting the web longitudinally, shear mechanism disposed in advance of said means and movable with the web of material, actuating means for

said shear mechanism, electrically controlled trip mechanism for tripping said shear actuating mechanism and a sheet trip for controlling the trip mechanism.

2. In a machine of the kind described for operating upon a web of material, the combination of means for slitting the blank longitudinally and simultaneously creasing the same, shear mechanism disposed in advance of said means, actuating means for the shear mechanism, and a sheet trip disposed at the rear of the slitting and creasing means to trip the shear actuating means.

3. In a machine of the kind described for operating upon a web of material, the combination of rotary slitting knives to slit the web longitudinally, shear mechanism disposed in advance of said slitting knives and adapted to cut the moving web transversely, actuating means for said shear mechanism, electrically controlled trip mechanism for tripping said shear actuating mechanism and a sheet trip for controlling said trip mechanism.

4. In a machine of the kind described for operating upon a web of material, the combination of two rotary shafts between which the web passes, coöoperating slitting knives on said shafts and coöoperating creasing blades on said shafts, the slitting knives being adapted to slit the web longitudinally and the creasing blades being adapted to provide longitudinal creases in the web, shear mechanism disposed in advance of said shafts to cut the web transversely, and means to actuate said shear mechanism.

5. In a machine of the kind described for operating upon a web of material, the combination of feed rolls adapted to feed the web to the machine, shear mechanism disposed at the rear of said feed rolls to cut the web transversely and movable with the web of material, slitting mechanism disposed at the rear of the shear mechanism to slit the web longitudinally, electrically controlled trip mechanism for tripping said shear actuating mechanism and a sheet trip for controlling said trip mechanism.

6. In a machine of the kind described for operating upon a web of material, the combination of feed rolls adapted to feed the web to the machine, longitudinally movable shear mechanism disposed at the rear of said feed rolls to cut the web transversely, combined slitting and creasing mechanism disposed at the rear of said shear mechanism designed to slit the web longitudinally and to provide the same with longitudinal creases, and a sheet trip disposed at the rear of said slitting and creasing mechanism to control the operation of the shear mechanism.

7. In a machine of the kind described for operating upon a web of material, the combination of means to provide the web with

creases, longitudinally movable shear mechanism disposed in advance of said means, actuating means for the shear mechanism, a sheet trip disposed at the rear of the 5 creasing means to trip the shear actuating means and feed rolls disposed in advance of the shearing mechanism for feeding the web of material to the latter.

8. In a machine of the kind described for 10 operating upon a web of material, the combination of rotary creasing blades to crease the web longitudinally, longitudinally movable shear mechanism disposed in advance of said means to cut the web transversely, 15 actuating means for said shear mechanism, a sheet trip disposed at the rear of said creasing blades to trip the shear actuating means and feed rolls disposed in advance of the shearing mechanism for feeding the web of 20 material to the latter.

9. In a machine of the kind described for 25 operating upon a web of material, the combination of rotary elements adapted to act upon the web, means to feed the web between such elements, shear mechanism for cutting 30 the web transversely, actuating means for said shear mechanism, and a sheet trip for tripping said actuating mechanism, the actuating mechanism being designed when tripped to cause the shear mechanism to cut the web transversely and being designed to reciprocate the shear mechanism longitudinally of the machine so that the shear mechanism will move with the web during 35 the shearing action.

10. In a machine of the kind described for 40 operating upon a web of material, the combination of means to feed the web through the machine, shear mechanism for cutting the blank transversely, electrically controlled 45 trip mechanism for controlling the operation of the shear mechanism and a sheet trip disposed in the path of movement of the trip for controlling said trip mechanism, and means to discharge the blanks cut from the web at a greater speed than the speed at 50 which the web is fed through the machine.

11. In a machine of the kind described for 55 operating upon a web of material, the combination of means to feed the web through the machine, shear mechanism for cutting the web transversely into blanks, a sheet trip adapted to be engaged by the forward edge of the web to control the operation of the shear mechanism, and means to discharge each blank after it is cut from the web and before its engagement with the sheet trip at a greater speed than the speed 60 at which the web is fed through the machine.

60 12. In a machine of the kind described for operating upon a web of material, the combination of means to feed the web through the machine, slitting and creasing mecha-

nism designed to slit the web longitudinally and to provide the same with longitudinal 65 creases, shear mechanism disposed in advance of said slitting and creasing mechanism designed to cut the web transversely into blanks, discharge belts disposed at the rear of said slitting and creasing mechanism, 70 a sheet trip adapted to be engaged by the forward portion of the web while the latter is supported by the discharge belts, means whereby said sheet trip controls the operation of the shear mechanism, and means to 75 operate said discharge belts at a greater speed than the speed at which the web is fed through the machine, for the purpose described.

13. In a machine of the kind described for 80 operating upon a web of material, the combination of feed rolls adapted to feed the web to the machine, means to operate said feed rolls at a predetermined speed, shear mechanism disposed at the rear of the feed 85 rolls to cut the web transversely into blanks, means to discharge the blanks cut from the web, and means to actuate said discharge means at a greater speed than the speed at 90 which said feed rolls are operated.

14. In a machine of the kind described for 95 operating upon a web of material, the combination of feed rolls to feed the web to the machine, means to actuate said rolls at a predetermined speed, shear mechanism disposed at the rear of said feed rolls to cut the web transversely into blanks, a sheet trip engageable by the front edge of the web to control the operation of the shear mechanism, and means to discharge the blanks 100 after they are cut from the web at a greater speed than the speed at which the feed rolls are actuated.

15. In a machine of the kind described for 105 operating upon a web of material, the combination of feed rolls to feed the web to the machine, means to actuate said rolls at a predetermined speed, shear mechanism disposed at the rear of said feed rolls to cut the web transversely into blanks, a sheet trip engageable by the front edge of the web to control the operation of the shear mechanism, a discharge belt for discharging the blanks from the machine after they are cut from the web, and means to actuate said discharge 110 belt at a greater speed than the speed at 115 which said feed rolls are actuated.

Signed at Rochester, in the county of Monroe, and State of New York, this 22 day of December A. D. 1915.
